UNITED STATES PATENT OFFICE.

JOSEPH SPESHA, OF NEW YORK, N. Y.

PROTECTIVE WRAPPER FOR INNER TUBES.

1,123,609.

Specification of Letters Patent.

Patented Jan. 5, 1915.

Application filed November 8, 1913. Serial No. 799,874.

To all whom it may concern:

Be it known that I, JOSEPH SPESHA, a citizen of the United States, and a resident of New York city, borough of Manhattan, in the county and State of New York, have invented a new and Improved Protective Wrapper for Inner Tubes, of which the following is a full, clear, and exact description.

10 My invention relates to a wrapper in which to carry a spare inner tube on an automobile.

15 The invention more especially relates to a wrapper having a means for receiving the projecting valve element and covering the same in a manner to effectively prevent the same from chafing the tube.

20 The invention consists in a wrapper having the novel features more particularly explained in the specific description following.

Reference is to be had to the accompanying drawings forming a part of this specification, in which similar characters of reference indicate corresponding parts in all 25 the views.

Figure 1 is a plan view of the inner side of a wrapper embodying my invention, showing the same in the open position, one corner being indicated as turned over to 30 show the outer side; Fig. 2 is a perspective view with the tube ready to be wrapped; Fig. 3 is a perspective view of the wrapper partially folded; and Fig. 4 is a perspective view showing the wrapper in its folded and 35 tied condition.

My improved wrapper 10 is in the form of a square or equivalent rectangular sheet, which in practice has a canvas or equivalent strong exterior 11, and a lining 12 of soft 40 material such as cotton flannel or wool. The wrapper is adapted to be folded successively on diagonal lines 13, which ordinarily are defined by stitching.

Disposed adjacent to the center of the 45 wrapper, at the inner side, is a protector 14, preferably of soft fabric to receive the projecting valve member of an inner tube A, the base of the valve fitting being indicated by the letter *a* in Fig. 2. The form, as well 50 as the material of the protector 14 is such that it will form a covering for the projecting member of the valve fitting to effectively prevent direct contact and rubbing of the said fitting when the tube A is wrapped and 55 stored in the automobile. As best seen in Fig. 1, the protector in the example shown,

is tubular and L-shaped, presenting an attaching member 14^a secured at one end as at 14^b, by one of the lines of stitching 13, to the inner face of the wrapper 10, and a lateral 60 L-arm 14^c at the free end, the extremity of the arm 14^c presenting a tubular entrance to receive the valve fitting. The line 14^b at the base of the protector 14 is thus diagonal to the sides of the sheet 10, and the lateral arm 65 14^c is therefore also disposed parallel with the diagonal line of attachment, and at an angle to the sides of the sheet. A tie strap or band 15 is secured to the sheet, preferably at one corner. The protector 14 is flexible and may be freely raised approximately 70 perpendicular to the inner surface of the sheet 10, so that when the tube A is folded and laid edgewise on the wrapper as in Fig. 2, the lateral arm 14^c may be positioned to 75 present its open end to the valve fitting *a*. With the tube thus positioned and its valve fitting protected as in Fig. 2, the corners 10^a at the right and left of the center are 80 successively folded onto the top of the tube, with one hand, the other hand of the user 85 serving to properly retain the tube A in the folded form as each end 10^a is placed in position and grasped by the hand holding the tube. The third corner 10^b opposite the tie strap or tape 15 is then snugly turned over onto the ends 10^a, and finally the remaining corner provided with the tie strap 90 is wrapped over the other folds in a manner to make a snug package, and the wrapper is then tied by means of the strap 15, it being understood that the free end of the strap 15 may be fastened in any suitable manner.

The wrapper effectively prevents chafing 95 of the tube by its valve fitting, and may be conveniently manipulated to properly wrap the tube.

Having thus described my invention, I claim as new and desire to secure by Letters Patent:

1. A wrapper for an inner tube, said wrapper having disposed thereon a flexible, tubular protection for the valve fitting of the tube, the protector being secured at one 105 end to the wrapper and having an opposite end free from the wrapper body, said free end presenting at its free terminal an opening for the entrance of the valve.

2. A wrapper for inner tubes, comprising 110 an approximately rectangular sheet of flexible material, and a protector disposed ad-

jacent to the center thereof and secured thereto, said protector being L-shaped and presenting a lateral arm disposed diagonally to the sides of the sheet.

5 3. A wrapper for an inner tube, comprising a sheet of flexible material and a protector thereon for the valve fitting of the tube, said protector having an arm extending laterally thereto adapted to receive the said fitting.

10 4. A wrapper for an inner tube, comprising a sheet of flexible material and a flexible protector thereon for the valve fitting of

the tube, said protector having a member secured at one end to the wrapper on a line 15 diagonal to the side of the sheet and presenting at its free end a lateral tubular member having an open end to receive the valve fitting.

In testimony whereof I have signed my 20 name to this specification in the presence of two subscribing witnesses.

JOSEPH SPESHA.
